UNITED STATES PATENT OFFICE.

TARGE G. MANDT, OF STOUGHTON, WISCONSIN.

DESIGN FOR A VEHICLE-HUB.

SPECIFICATION forming part of Design No. 35,485, dated December 24, 1901.

Application filed November 6, 1901. Serial No. 81,332. Term of patent 7 years.

To all whom it may concern:

Be it known that I, TARGE G. MANDT, a citizen of the United States, residing at Stoughton, in the county of Dane and State of Wisconsin, have invented and produced a new and useful Design for Vehicle-Hubs, of which the following is a specification.

My invention relates to a new and useful design for a vehicle-hub, of which the following is a specification, reference being had to the accompanying drawings, in which—

Figure 1 is a perspective of my hub. Fig. 2 is an end elevation of the same. Fig. 3 is a side elevation of the same.

Like numerals of reference designate like parts in the different views of the drawings.

The numeral 1 designates the body portion, which has a rim 2 formed centrally thereon and is beveled both ways from the rim toward the ends. Circular beads 4 are formed at the junction of the body 1 and the rim 2. A rim 5 is formed on one end of the body 1 and a threaded boss 6 on the other. The rim 5 is beveled off on its inner side.

Formed in the rim 2 are beveled rectangular spoke-sockets 7, having converging sides 7^a. While the rim 2 is circular, rounded notches 8 are formed intermediate each of the spoke-sockets.

The essential or material features of my design are the oppositely-beveled body portion 1, with a beveled rim 5 on its rear end, a boss 6 on its forward end, and a circular rim 2, formed centrally on said body and having beveled spoke-sockets 7 therein with intervening rounded notches 8.

Having described my invention, what I claim as new, and wish to secure by Letters Patent, is—

The design for a vehicle-hub, substantially as shown and described.

In testimony whereof I have hereunto set my hand in presence of two subscribing witnesses.

TARGE G. MANDT.
